(57) **CLAIM**

The ornamental design for a combined disposable tray, sterile barrier, and non-sterile device, as shown and described.

DESCRIPTION

FIG. 1 is a left side perspective view of a combined disposable tray, sterile barrier, and non-sterile device, showing only the disposable tray;

FIG. 2 is a left side perspective view thereof, showing only the disposable tray and the sterile barrier, the sterile barrier attached to the disposable tray in an open position;

FIG. 3 is a left side perspective view thereof, showing the disposable tray, the sterile barrier, and the non-sterile device, the sterile barrier shown as receiving the non-sterile device;

FIG. 4 is a left side perspective view thereof, showing the disposable tray, the sterile barrier, and the non-sterile device, the non-sterile device spaced from the disposable tray and the sterile barrier;

FIG. 5 is a left side perspective view thereof, showing only the disposable tray and the sterile barrier of FIG. 2 with the disposable tray spaced from the sterile barrier;

FIG. 6 is a left side perspective view thereof, showing only the disposable tray and a coupler of the sterile barrier of FIG. 2 with the disposable tray spaced from the coupler of the sterile barrier with the sterile barrier removed from the coupler;

FIG. 7 is a rear view thereof, showing only the disposable tray of FIG. 1;

FIG. 8 is a front view thereof, showing only the disposable tray of FIG. 1;

FIG. 9 is a rear view thereof, showing only the disposable tray and the sterile barrier of FIG. 2;

FIG. 10 is a front view thereof, showing only the disposable tray and the sterile barrier of FIG. 2;

FIG. 11 is a rear view thereof, showing the disposable tray, the sterile barrier, and the non-sterile device of FIG. 3;

FIG. 12 is a front view thereof, showing the disposable tray, the sterile barrier, and the non-sterile device of FIG. 3;

FIG. 13 is a side elevation view thereof, showing only the disposable tray of FIG. 1, the other side being a mirror image thereof;

FIG. 14 is a side elevation view thereof, showing only the disposable tray and the sterile barrier of FIG. 2, the other side being a mirror image thereof;

(Continued)

FIG. 15 is a side elevation view thereof, showing the disposable tray, the sterile barrier, and the non-sterile device of FIG. 3, the other side being a mirror image thereof; FIG. 16 is a side elevation view thereof, showing the disposable tray, the sterile barrier, and the non-sterile device of FIG. 4, the other side being a mirror image thereof; FIG. 17 is a side elevation view thereof, showing only the disposable tray spaced from the sterile barrier of FIG. 5, the other side being a mirror image thereof; FIG. 18 is a side elevation view thereof, showing only the disposable tray spaced from the coupler of the sterile barrier of FIG. 6 with the sterile barrier removed from the coupler, the other side being a mirror image thereof; FIG. 19 is a top view thereof, showing only the disposable tray of FIG. 1; FIG. 20 is a top view thereof, showing only the disposable tray and sterile barrier of FIG. 2; FIG. 21 is a top view thereof, showing the disposable tray, the sterile barrier, and the non-sterile device of FIG. 3; FIG. 22 is a top view thereof, showing only the disposable tray and the coupler of FIG. 6; FIG. 23 is a bottom view thereof, showing only the disposable tray of FIGS. 1-3; FIG. 24 is a left side perspective view thereof, showing the disposable tray and the sterile barrier and the non-sterile device of FIG. 3 with the sterile barrier extended to an extended unzipped position about the non-sterile device; FIG. 25 is a left side perspective view thereof, showing the disposable tray of FIG. 24 in an extended zipped position; FIG. 26 is a left side perspective view thereof, showing the disposable tray of FIG. 25 in the extended zipped position with an adhesive strip removed from a flap; and,

FIG. 27 is a left side perspective view thereof, showing the disposable tray of FIG. 26 in the extended zipped position with flap folded over to adhere to the other side. The dotted lines in FIG. 23 depict portions of the combined disposable tray, sterile barrier, and sterile device that form no part of the claimed design. The remaining dashed lines in the drawings depict environmental subject matter and form no part of the claimed design.
